UNITED STATES PATENT OFFICE.

ARTHUR THOMAS ELLIS, OF LONDON, ENGLAND, ASSIGNOR OF ONE-HALF TO HARRY ARTHUR HANDS, OF LONDON, ENGLAND.

VALVE OF INTERNAL-COMBUSTION ENGINES.

1,329,321.

Specification of Letters Patent. Patented Jan. 27, 1920.

Application filed August 8, 1919. Serial No. 316,251.

To all whom it may concern:

Be it known that I, ARTHUR THOMAS ELLIS, a subject of the Kingdom of Great Britain, residing at 129 Castelnau, Barnes, London, S. W., in the county of Middlesex, England, have invented certain new and useful Improvements in and Relating to the Valves of Internal-Combustion Engines, of which the following is a specification.

10 This invention comprises certain improvements in or relating to the valves of internal-combustion engines, and refers to the type in which a collar or member is screwed upon the stem of the valve against or upon 15 which the valve spring is adapted to bear for the operation of the valve, and in which means adapted to be assembled substantially laterally or transversely of the length of the valve stems are provided for normally preventing the collar from becoming un-screwed.

According to the present invention a spring bearing collar having direct screw connection with the valve stem is normally 20 prevented from unscrewing by means of a locking piece or member which is adapted to be assembled substantially laterally or transversely of the valve stem against a shoulder formed by grooving the annular 25 face of the valve stem itself. The locking piece or member may be in the form of a slotted and centrally apertured cone and the spring bearing collar may have a cone shaped recess with which the coned locking 30 piece is adapted to be engaged.

The locking member may be in the form of an apertured cone which is split into two halves and these halves may be united by a suitable spring or wire so that same can 40 readily be made to embrace the valve stem by opening the two halves against the action of the spring or said cone may be radially slotted to its central aperture to enable same to be engaged with the annular groove 45 in the valve stem.

In order that this invention may be clearly understood and readily carried into practice, reference may be had to the appended explanatory sheet of drawings, upon 50 which:—

Figure 1 illustrates in sectional elevation a valve fitted according to the present invention.

Fig. 2 is an enlarged plan of the supplementary collar shown in Fig. 1.

Fig. 3 illustrates in sectional elevation a valve fitted with a modified embodiment of the present invention.

Fig. 4 is an enlarged plan of the supplementary collar shown in Fig. 3.

In a convenient embodiment of the present invention, that part of the valve spindle *a* adjacent the outer end of the spring *b* is screw-threaded around its circumference for a distance extending within the spring; a 60 collar *c* of suitable diameter to form an abutment to the end of the spring is adapted to be screwed on to the threaded part of the spindle, in such a manner as to enable the spring to be compressed by the turning 65 of the collar. That face of the collar facing the end of the spring is preferably cupped to form a recess *d* in which the end of the spring rests.

At the outer end of the screw thread, the 70 spindle is reduced in diameter so as to form an annular shoulder *e*. The outside face of the collar is provided with an annular cone-shaped recess *f*.

A supplementary cone-shaped split collar 80 *g* is adapted to be placed around the reduced portion of the spindle when the spring has been compressed by the main collar being screwed along the spindle, such supplementary split collar being retained in position with its lower flat face abutting against the shoulder on the spindle by the cone recess *f* in the main collar when such main collar is screwed along the spindle in the reverse direction which allows of the expansion 85 of the spring.

The two parts of the supplementary split collar *g* are connected together by a spring *h* which is arranged so as to allow of the split collar being opened for the purpose 90 of inserting it around the neck of the spindle, such spring being adapted automatically to close the supplementary split cone when in position.

For enabling the supplementary split collar to be readily placed in engagement with the neck of the spindle, the faces *i* of the split at one side of the collar may be inclined to form an inwardly converging mouth so that upon pressing the mouth 100 against the neck of the spindle the two sides of the supplementary collar will readily embrace the neck of the spindle.

The split on the reverse or hinge side of the supplementary collar may also be of 110

form converging inwardly so as to allow the mouth on the opposite side of the split to more readily open.

A groove or recess may be provided around 5 the outside edge of the two parts of the supplementary collar within which the steel wire or ribbon spring *h* may be inserted, which spring is so shaped as to embrace a substantial part of the circumference of the 10 split collar, any appropriate provision being made to prevent the spring from working around the groove into a position in which it would cover the mouth of the split.

The outer circumference of the main collar 15 may be milled as at *j* to enable the collar to be more readily screwed, and holes *k* may be provided around the circumference for the insertion of any article such as a wire nail for assisting in turning the 20 collar when compressing the spring.

That part of the spindle which is provided with a screw-thread is larger in diameter than the end part *l* of the spindle to the extent of the depth of the screw- 25 thread, so as to allow the main collar when free of the screw to slip freely over the remaining portion of the spindle.

The main collar may be provided with a sleeve portion *m* which projects into the 30 end of the spring, and which sleeve is tapped in addition to the interior of the collar so as to afford a greater length of screw-threaded travel of the collar upon the spindle. In the arrangement shown, this 35 sleeve enables the collar to be engaged with the stem in circumstances in which the spring in its extended position projects below the lower extremity of the screwed portion of the stem.

40 In a modified embodiment of the present invention shown in Figs. 3 and 4, the supplementary cone-shaped collar comprises a unitary member *n* which is provided with a slot *o* adapted to allow of the collar being 45 slid on to the reduced portion of the spindle when the spring has been compressed by the main collar being screwed along the spindle in one direction, such supplementary collar being retained in position with its flat face abutting against the shoulder on the spindle by the cone recess in the main collar when such main collar is screwed along the spindle in the reverse direction which allows of the expansion of the spring.

The action of releasing the valve is as follows:—

The main collar is screwed along the spindle against the compression of the spring until the coned recess in the collar is clear

of the supplementary collar, which is then 60 removed from the neck of the spindle, the main collar being then screwed the reverse way until clear of engagement with the screw-thread on the spindle, which then renders the valve free to be removed. 65

The action of inserting the valve is as follows:—

The end of the spindle is placed within the spring and main collar, which main collar is then engaged with the screw-thread 70 and screwed in the direction to compress the spring until the outside face of the collar is clear of the neck on the spindle. The supplementary collar is then engaged with the neck and the main collar screwed back 75 again until its coned recess operates upon the cone-shaped split collar, thereby gripping the split collar around the neck with its outer face in engagement with the shoulder on the spindle. 80

What I claim as my invention and desire to secure by Letters Patent is:—

1. In combination with a valve stem having a threaded portion and an unthreaded, diametrically reduced portion between the threaded portion and the inner end of the stem, a spring-bearing collar screwed on said threaded portion and having a conical recess opposite said reduced portion of the stem, and a locking member having a conical 90 portion to enter said conical recess, an opening to receive said reduced portion and also a slot leading from one side of said member to said opening to permit assembling and disassembling of said stem, collar and locking member. 95

2. In combination with a valve stem having a threaded portion and an unthreaded, diametrically reduced portion between the threaded portion and the inner end of the 100 stem, a spring-bearing collar screwed on said threaded portion and having a conical recess opposite said reduced portion of the stem, and a locking member having a conical portion to enter said conical recess, an opening to receive said reduced portion and also a slot leading from one side of said member to said opening to permit assembling and disassembling of said stem, collar and locking member, said member comprising a 110 pair of sections and a spring flexibly connecting said sections together. 105

In witness whereof I have hereunto set my hand in the presence of two witnesses.

ARTHUR THOMAS ELLIS.
